TREATING HYDROCARBON OILS

William M. Stratford, New York, N. Y., assignor
to The Texas Company, New York, N. Y., a corporation of Delaware

Application November 16, 1932, Serial No. 642,861

5 Claims. (Cl. 196—35)

This invention relates to the treatment of hydrocarbon oils and more particularly to the treatment of distillates obtained by cracking petroleum hydrocarbons which may contain unstable, unsaturated compounds and undesirable organic sulfur derivatives.

The invention contemplates a method of treating and purifying hydrocarbon oils such as cracked naphtha containing either unstable, unsaturated compounds having gum forming tendencies, or sulfur derivatives, or both, which includes subjecting the naphtha to treatment with alkali metal or alkaline earth metal at elevated temperatures and pressures whereby the undesirable unsaturated compounds are polymerized to compounds of higher boiling point and the obnoxious sulfur derivatives are substantially decomposed. The treated naphtha is then separated from the polymers and residues and is fractionated to yield a color and gum stable naphtha of the desired boiling point range.

The invention will be fully understood from the following description thereof considered with the drawing which represents in diagrammatic sectional elevation an apparatus which may be used for carrying out the process. The apparatus illustrated in the drawing is shown and described merely for the purpose of aiding and understanding the process, and it is to be understood that any other suitable apparatus may be substituted for that shown in the drawing.

In the drawing, the numeral 10 designates a suitable storage tank for the cracked naphtha to be treated. This storage tank is fitted with a drawoff line 11 controlled by the valve 12 which enters the intake side of the pump 13. This pump discharges through the line 14 controlled by the valve 15 which communicates with the coil 16 of the heater 17. The numeral 20 indicates a mixing chamber which also serves as a storage for liquid sodium. This mixing chamber is provided with a mechanical stirrer 21 and a heating coil 22 through which a suitable heating medium may be circulated. The bottom of this mixer is fitted with a drawoff line 24 controlled by the valve 25 which communicates with the inlet side of a pump 26. This pump discharges through the line 28 and the valve 29 into the heating coil 16 of the preheater 17 at a point intermediate the ends of the heating coil.

The discharge of the heating coil 16 communicates through the line 31 and the valve 32 with the interior of the flash chamber 34. The uppermost point of the flash chamber is provided with

a vapor line 35 while the bottom is fitted with a liquid drawoff line 36 controlled by the automatic valve 37. The interior of the flash chamber 34 is advantageously fitted with a tray 38 of Raschig rings or similar refractory contact materials, as well as baffle plates 40 for preventing the carrying over of liquid into the vapor line 35. The drawoff line 36 connects the bottom of the flash chamber 34 with a separatory chamber 41. The top of this separatory chamber is provided with a liquid drawoff line 42 controlled by the valve 43 while the bottom of the separatory chamber is fitted with a drawoff line 44 controlled by the valve 45 which connects the separatory chamber with the rotating retort 47. This retort is revolvable and is fitted with a vapor line 48 controlled by the valve 49 which enters the fractionating tower 50 at a lower point in the structure, while the bottom of the still is fitted with the drawoff line 51 controlled by the valve 52.

The fractionating tower 50 is fitted at its uppermost point with a vapor drawoff line 54 controlled by the valve 55 which leads to a suitable condensing system (not shown). The bottom of the fractionating tower is provided with a drawoff line 56 controlled by the automatic valve 57 and the manually operated valve 58 which leads to a suitable storage. There is manifolded to the line 56 at a point intermediate the valves 57 and 58 the line 59 controlled by the valve 60 which connects with the intake of the pump 61. This pump discharges through the line 62 into the mixing chamber 20.

The vapor line 35 which leaves the top of the flash chamber 34 connects this chamber through the valve 64 with the treated naphtha fractionating tower 65. This fractionating tower is fitted at an upper point in its structure with a reflux cooling coil 66 and at a lower point in its structure with a steam spray 68.

The bottom of the tower is fitted with a drawoff line 69 controlled by the automatic valve 70 and the valve 71. This drawoff line leads to a suitable storage tank not shown. There is manifolded to the line 69 at a point between the valve 70 and 71 the line 72 controlled by the valve 73 which connects through the pump 75 with the mixing chamber 20.

The top of the fractionating tower 65 is provided with the vapor line 77 controlled by the valve 78 which communicates with the cooling coil 79 of the condenser 80. The cooling coil 79 discharges through the line 81 controlled by the

valve 82 which line leads to a storage tank not shown.

In a typical operation of the process which is embodied by my invention, cracked naphtha distillate which is stored in the storage tank 10, is delivered to the pump 13 through the line 11 in controlled quantity. This pump may be of any type suitable for high pressure work and which is capable of delivering pressures up to 3000 lbs. per square inch. The naphtha is then charged into the heating coil 16 under a suitable pressure, for example, about 2000 lbs. per sq. in. which is sufficient to maintain the naphtha substantially in the liquid phase under the conditions of temperature which obtain in the heating coil. A suitable temperature of 800 to 900° F. may be maintained at the outlet of the heating coil 16.

Metallic sodium, in finely divided form, is withdrawn from the mixing chamber 20 through the line 24 and the valve 25, and is injected by means of the pump 26 into the heating coil 16 at a point intermediate the ends of the coil. The finely divided sodium and the naphtha are intimately mixed in the coil of the preheater and, under the conditions of temperature and pressure prevailing therein, the sodium catalyzes the polymerization of the undesirable, unsaturated compounds present in the cracked naphtha. At the same time, some of the sodium combines chemically with the sulfur of the organic sulfur compounds present in the naphtha to yield sodium sulfide. The unsaturated organic compounds, which are formed by the decomposition of the organic sulfur compounds, tend to polymerize to form high boiling hydrocarbon compounds.

The quantities of sodium used in this operation may vary widely depending upon the quantities of unsaturates originally present in the cracked naphtha, upon the quantity of sulfur present in the organic sulfur compounds and upon the quantity of unsaturates formed by the decomposition of the sulfur compounds. The time of reaction between the cracked naphtha and the sodium may be prolonged by increasing the length of the heating coil in the preheater.

By the proper control of the above mentioned variables affecting the reaction, substantially all of the undesirable, unsaturated compounds may be polymerized and a large proportion of the sulfur compounds decomposed. In such a case, the discharge from the heating coil 16 will comprise a mixture of treated naphtha distillate, polymers, unreacted sodium, and sodium sulfide. This mixture is discharged through the line 31 and the valve 32 into the flash chamber 34 wherein the pressure may be reduced to a value determined by the type of naphtha used and the pressures and temperatures maintained in the heating coil 16. Within the flash chamber the treated naphtha is vaporized and passes upwardly through the chamber in the paths determined by the structure of the baffles 40. The vapors are drawn off from the top of the flash chamber through the vapor line 35 and through the valve 64, and are discharged into a lower point of the fractionating tower 65.

The fractionating tower 65 serves in the fractionation of the treated naphtha vapors. The temperatures within the tower may be regulated by the cooling supplied to the top of the tower by the cooling coil 66 and by the steam injected into the bottom of the tower through the steam spray 68. By the proper control of these factors affecting the temperature difference within

the tower, it is possible to fix the boiling point range of the vapors which are drawn off from the top of the tower, as well as of the residual oil, a pool of which is maintained in the bottom of the tower.

In the operation of the fractionating tower 65, it is desirable that a certain quantity of steam be injected into the bottom thereof through the steam spray 68 for the purpose of decomposing any minute particles of metallic sodium that may be carried over from the flash chamber 34 through the vapor line 35. The use of steam in this way prevents the dangerous accumulations of sodium in the bottom of the tower 65 and in the storage tank to which the residual oil drawn off from the tower may be discharged.

The treated fractionated vapors drawn off through the vapor line 71 are passed into the cooling coil 79 of the condenser 80 wherein they are substantially condensed. The treated condensate produced in this manner, which comprises a merchantable naphtha distillate is drawn off through the line 81 controlled by the valve 82 and passes to a suitable storage.

The residual oil, a controlled body of which is maintained in the bottom of the tower, may be withdrawn through the line 69 controlled by the automatic valve 70 and the manually operated valve 71, and is discharged to a suitable storage tank. Under certain conditions of operation, it may be desirable to withdraw a certain quantity of this residual oil through the line 72 controlled by the valve 73 by means of the pump 75, which pump discharges the oil to the mixer 20.

The mixing chamber 20 serves as a storage for sodium and such oil as is used in admixture with the sodium. The oil serves primarily to prevent the oxidation of the sodium and to assist in the proper subdivision of the sodium particles. It has been found that by using a heavy oil such as may be produced as a residual oil in the fractionating chamber 65, that extremely fine subdivision of the sodium is possible.

The residuum which collects as a pool in the bottom of the flash chamber 34 and which consists of a mixture of polymers comprising hydrocarbons of higher boiling point than the raw naphtha charge, sodium and sodium sulfide, is withdrawn through the line 36 and the automatic valve 37 and is delivered into the separatory chamber 41 wherein the mixture is allowed to stratify. The supernatant liquid polymers may be drawn off through the line 42 controlled by the valve 43 and delivered to suitable storage, while the lower layer of sodium, sodium sulfide and small quantities of polymers are drawn off through the line 44 and the valve 45 and delivered to the rotating retort 47 which is maintained at a temperature preferably above the boiling point of sodium. The hydrocarbon polymers and sodium are vaporized and pass into the tower 50, which serves as a fractional condenser for condensing the vapors of the sodium which collects as a pool in the lower portion thereof. The vapors of the polymers, including vapors of hydrocarbon decomposition products thereof, pass upward and are drawn off from the top of the tower through the vapor line 54 controlled by the valve 55, and passed to a condensing system (not shown) wherein the hydrocarbon vapors are substantially condensed. The hydrocarbons so obtained are extremely unsaturated products and may serve as a potential source of resins and gum-like materials suitable for use in the arts.

The liquid sodium at the bottom of the tower 75

50 is drawn off through the line 56 controlled by the automatic valve 57 and the valve 58 to a suitable storage. In most operations of the process, the sodium may, with advantage, be drawn off through the line 59 which is manifolded to the line 56 at a point intermediate the valves 57 and 58, passed through the valve 60 and the pump 61 into the line 62 which discharges into the mixing chamber 20.

10 The residue remaining in the still 41 may be drawn off through the drawoff line 51 controlled by the valve 52. In those cases where this residue is extremely viscous or non-fluid, it may be necessary to operate the still on the batch principle.

15 A scraper or the like may be incorporated in the still structure to facilitate the withdrawal of the bottoms.

The disposal of the residues which are formed as by-products in the treatment of unsaturates 20 with alkali metals has always been attended by the difficulty of converting any traces of sodium into inactive compounds. This is a necessary precaution since sodium will react with water with explosive violence and the liberation of great 25 heat and therefore is a source of great danger. I have found that this difficulty may be overcome by exposing the sodium residues such as are drawn off from the still 41 to the action of a limited amount of flue gas or carbon dioxide 30 whereby some of the sodium sulfide is decomposed to yield hydrogen sulfide which then reacts with any free unreacted sodium to form the relatively inactive sodium sulfide.

At the temperatures of reaction maintained in 35 the operation of this process, the sodium does not react with the unsaturates to form the well-known loosely bound sodium compounds insoluble in naphtha but appears to act catalytically on the unsaturates to form polymers without it- 40 self being consumed. This catalytic action of sodium is first noticed at temperatures of from 400 to 500° F. At temperatures lower than this, the sodium does not appear to display this catalytic action but merely reacts with the un- 45 saturates to form the so-called sodium residues constituting sodium-hydrocarbon complex compounds insoluble in naphtha.

The polymerizing activity of the sodium appears to be paralleled by the desulfurizing activ- 50 ity insofar as the temperature is concerned. At temperatures below 500° F. the sodium does not react energetically with the hydrocarbon-sulfur compounds and, as a result, a large proportion of the stable sulfur derivatives remain unreacted. 55 At temperatures above this, the desulfurizing action becomes more and more vigorous and at temperatures in the neighborhood of 900° F. the sodium actively decomposes all of the sulfur compounds. The mechanism of the reaction may be 60 as follows: The sodium unites with the sulfur to form sodium sulfide, simultaneously liberating unsaturated hydrocarbons. These unsaturated molecules are then polymerized in the presence of metallic sodium to form high molecular weight 65 compounds such as gums or polymers of higher boiling point.

From the above consideration, it is apparent that the proper operating temperature for the process is determined in large measure by the 70 reactivity of the unsaturated compounds present in the naphtha undergoing treatment, as well as by the stability of the sulfur derivatives and, al- though a temperature of 900° F. appears to be

the most advantageous under ordinary conditions, the use of still higher temperatures, in certain specific cases, may be desirable for the most successful operation of the process.

Obviously many modifications and variations 5 of the invention, as hereinbefore set forth, may be made without departing from the spirit and scope thereof, and therefore only such limitations should be imposed as are indicated in the ap- 10 pended claims.

I claim:

1. A method of treating and purifying a cracked naphtha distillate containing undesirable sulfur compounds and unsaturated hydrocarbons which comprises mixing the naphtha 15 distillate with an alkali metal to form a mixture, heating the mixture to a temperature of the order of 800 to 900° F. and under superatmospheric pressure whereby the undesirable unsaturated compounds are polymerized and the sulfur com- 20 pounds are decomposed to yield residues, separating the treated naphtha distillate from the polymers and residues and distilling it to yield a fraction of the proper boiling point range.

2. A continuous process of treating and puri- 25 fying a cracked naphtha distillate containing un- desirable unsaturated hydrocarbons which com- 30 prises continuously charging the cracked naphtha distillate to a heating coil, simultaneously com- mingling with the naphtha a measured quantity of sodium suspended in a hydrocarbon medium to form a mixture, heating the mixture to a temperature of the order of 800 to 900° F. under superatmospheric pressure whereby the unsatu- 35 rated hydrocarbons are catalytically polymerized by the sodium, then continuously separating the treated naphtha from the polymers and sub- 40 jecting it to a fractionation to produce a motor fuel of the proper boiling point range.

3. In the refining of a cracked naphtha distil- 45 late, the step which includes heating the cracked naphtha distillate to a temperature of from 800 to 1000° F. in the presence of a finely divided alkali metal polymerizing catalyst.

4. A method of treating and purifying a 50 cracked naphtha distillate containing unstable unsaturated compounds and obnoxious sulfur de- 55 rivatives which comprises heating the naphtha distillate with sodium to a temperature of the order of 800 to 900° F. and under a pressure of between 1000 and 2000 lbs. per sq. in. Whereby the undesirable unsaturated compounds are poly- merized to compounds of higher boiling point and the obnoxious sulfur compounds are decom- 60 posed to form residues, separating the treated naphtha from the polymers and residues and fractionating it to yield a color and gum stable naphtha of the desired boiling point range.

5. A method of treating and purifying a cracked naphtha distillate containing unstable 65 unsaturated compounds and obnoxious sulfur de- 70 rivatives which comprises heating the naphtha distillate with sodium to a temperature in the neighborhood of 900° F. and under a pressure of about 400 lbs. per sq. in. whereby the undesirable, unsaturated compounds are polymerized to com- 75 pounds of higher boiling point and the obnoxious sulfur compounds are decomposed to form resi- 80 dues, separating the treated naphtha from the polymers and residues and fractionating it to yield a color and gum stable naphtha of the de- 85 sired boiling point range.

WILLIAM M. STRATFORD.
